His Attorney.

UNITED STATES PATENT OFFICE

CHARLES C. ABBOTT, OF PITTSFIELD, MASSACHUSETTS, ASSIGNOR TO GENERAL ELECTRIC COMPANY, A CORPORATION OF NEW YORK

ELECTRIC HEATER

Application filed October 15, 1925. Serial No. 62,627.

My invention relates to electric heaters, and more particularly to moisture proof electric heaters, and has for its object the provision of improved means for sealing heaters of this type.

My invention has special application to electric heaters of the encased or sheathed type in which the heater is enclosed in an outer metallic protective casing and is there-
10 by made impervious to moisture except at the points where the terminals project from the casing.

In carrying out my invention, I shape the encased heating unit so that its ends are ad-
15 jacent each other and provide a receptacle on the protective casing of the unit adjacent its ends in which is an insulating sealing mate-
rial which embeds the ends of the casing and the terminals projecting therefrom, as de-
20 scribed and claimed in my co-pending appli-
cation Serial No. 595,191, filed October 17,
1922. In accordance with my present inven-
tion I close the receptacle by means of a solid
25 insulating block which is provided with aper-
tures for the terminals and with an extension
extending into the insulating material whereby
the block is secured.

For a more complete understanding of my invention reference should be had to the ac-
30 companying drawing in which Fig. 1 is a
fragmentary plan view partly in section of
an electric heater embodying my invention;
Fig. 2 is a fragmentary side elevation view
35 also partly in section of the heater shown in
Fig. 1; while Fig. 3 is a fragmentary sec-
tional view taken along the line 3—3 of Fig.
1 looking in the direction of the arrows.

Referring to the drawing, I have shown my invention in one form in combination with a
40 helical coil sheathed heating unit of the type
described and claimed in my Patent No.
1,367,341, dated February 1, 1921. Briefly,
this heating unit 10 comprises an outer metal-
45 lic sheath 11 in which a helical resistance con-
ductor 12 is embedded in a compacted mass
of powdered heat refractory electrically in-
sulating material 13. The insulating mate-
rial 13 may be compacted to a hard dense
50 mass having good heat conductivity in any
suitable manner, for example, by reducing

the diameter of the sheath after the unit has
been assembled. Such units can be bent easily
into any desired shape, and as shown, the
heating unit 10 is bent in the form of a hair-
pin. The resistance conductor 12 has its ends
55 secured to terminals 14 and 15, which project
from the ends of the sheath and are electric-
ally insulated from the sheath.

As shown, the central portion of the heat-
ing unit is cast in a mass or body of metal 16,
such as cast iron, whereby the unit may be
secured to the body or member to be heated,
as, for example, by means of suitable clamp-
60 ing bolts passing through notches 17 and 18
provided in the ends of the body 16. As
65 shown, the body 16 has a flat surface 19 which
may be secured in good heat conducting rela-
tion to a similar flat surface on the part to
be heated. In the casting of the heating unit
in the body 16 a plurality of metallic washers
70 20 are secured at intervals along its length
whereby the heating unit is upheld in the
proper position in the mould, while the metal
is cast around it. These washers remain in
75 the casting.

Substantial lengths of the ends of the
heating unit project from the cast body 16
and these ends 21 and 22 are bent upward
with respect to the surface 19 so as to be out
of the way. These ends of the heating unit
80 are brought near each other and in order to
provide a moisture proof seal a receptacle
member 23 is secured to them. This recep-
tacle member has apertures in its bottom
through which the ends of the heating unit
85 are inserted so as to project somewhat into
the interior of the receptacle after which
the receptacle is secured to the sheath by
brazed or welded joints 24 and 24^a. An elec-
trically insulating sealing material 25 is pro-
90 vided in the receptacle, this sealing material
being poured into the receptacle while heat-
ed to a liquid condition. The sealing mate-
rial embeds the outer ends of the heating
units and the terminals, thoroughly sealing
95 the ends of the heating unit. Any suitable
sealing material may be used, such as bak-
elite or an asphaltic compound.

The receptacle is further closed by means
of a solid cylindrical block of suitable insu-
100

lating material 26 provided with apertures 27 and 28 for the terminals. This block which may be made of lava, is slightly larger than the mouth of the receptacle and rests on the 5 upper edge of the receptacle, completely closing it. It is provided with an extension 29 on its lower side which projects downward into the sealing material 25. Preferably the block 26 is put in place while the sealing material 10 is still soft so that the sealing material is free to flow around the extension 29 and secure the block in place upon hardening. The block is further secured by means of contact clips 30 and 31, which are electrically 15 connected to the ends of the terminals and seated firmly on the block. A cap 32 is provided, which is secured to the receptacle by means of screws 33 and encloses the contact clips 30 and 31. An insulating bushing 34 is 20 provided in the cap through which conductors may be led to the contact clips in order to connect the heater to a suitable source of electrical supply.

What I claim as new and desire to secure 25 by Letters Patent of the United States is:—

1. A water-tight seal for heating units provided with a metallic sheath which has its ends substantially adjacent each other and from which electrical terminals project comprising a receptacle secured to said sheath near its ends so that said ends project into said receptacle, an insulating sealing material in said receptacle embedding the ends of said sheath and said terminals, a block of 30 solid insulating material closing said receptacle and provided with apertures for said terminals, said block having an extension 35 extending into said receptacle and embedded in said insulating material and a contact clip provided for each terminal and mounted upon the end thereof in engagement with said insulator so as to secure said insulator.

2. A water-tight seal for heating units provided with a metallic sheath which has its ends substantially adjacent each other and from which the terminals of an insulated resistance conductor project comprising a receptacle secured to said sheath near its ends so that said ends project into said receptacle, 45 an insulating sealing material in said receptacle embedding said terminals and the projecting ends of said sheath, an insulator embedded in said sealing material closing said receptacle and provided with apertures for 50 said terminals and a terminal clip provided for each terminal and mounted upon the end thereof in engagement with said insulator so as to secure said insulator.

60 In witness whereof, I have hereunto set my hand this 10th day of October, 1925.

CHARLES C. ABBOTT.
